UNITED STATES PATENT OFFICE.

GENKICHI YAMANOUCHI, OF EBARAGUN, TOKYO, JAPAN.

FIREPROOF STONE.

1,409,329.

Specification of Letters Patent. Patented Mar. 14, 1922.

Application filed June 9, 1919. Serial No. 302,855.

To all whom it may concern:

Be it known that GENKICHI YAMANOUCHI, a subject of the Emperor of Japan, residing at No. 124 Nakano-cho, Yawato, Omori-machi, Ebaragun, Tokyo Province, Japan, has invented certain new and useful Improvements in Fireproof Stone, of which the following is a specification.

This invention relates to improvements in 10 fire-proof concrete blocks and more particularly to building blocks.

The primary object of the invention is to furnish a block having a large interior space, and the ends of the block are provided with small apertures which communicate 15 with the space.

Another object of the present invention is to provide an improved block of the above character which when incorporated in a wall 20 formed of similar blocks, will provide a wall having the same or greater strength at the joints as through any portion of the blocks. As the top and bottom wall of the blocks are comparatively thick in section, the blocks 25 when superposed in the wall will have at least equal or perhaps greater strength at the joints than in any other section through the blocks. This is a very important feature as in many localities, laws or regulations 30 are in force in connection with building construction which require that the joints be at least equal in strength to the other portions of the wall.

Blocks constructed in accordance with the 35 present invention have side recesses which are adapted to receive vertical reinforcing bars and mortar that secures the blocks in position, and the apertures in the end walls of each block are spaced from the side recesses so that the mortar used at the sides 40 of the block is not liable to enter and obstruct said apertures. The block is also provided with upper and lower grooves which are arranged at each side of the apertures in the end walls of the block and are 45 adapted to receive horizontally arranged reinforcing bars and mortar for securing these bars in position. A wall constructed with blocks of this character has unobstructed 50 vertical passageways which extend from the top to the bottom of the wall and these passageways may be utilized for the storage of electric conduits, sound tubes, plumbing pipes, etc. Moreover, air in the vertical passageways may circulate and maintain the 55 blocks in dry condition.

The invention is illustrated in the accompanying drawings in which:

Figure 1 is a side view of one of the improved blocks.

60

Fig. 2 is a face view of the same.

Fig. 3 is a top plan view of the block.

Fig. 4 is a vertical transverse sectional view of the block.

Fig. 5 is a vertical longitudinal sectional view of the block.

Fig. 6 is a horizontal sectional view taken intermediate the ends of the block.

Fig. 7 is a horizontal sectional view taken through one of the end walls of the block.

70

Fig. 8 is a detail view of a portion of a building formed of the improved blocks.

Fig. 9 is a horizontal sectional view of the construction shown in Figure 8.

Fig. 10 is a perspective view of a portion 75 of a building formed of the improved blocks.

Fig. 11 is a detail perspective view of a portion of a wall formed of the blocks, partly broken away for the purpose of illustration.

80

The building block according to the present invention is preferably formed of concrete and is of rectangular shape as best shown in Figures 1 to 7 of the drawings. The block preferably consists of front and 85 rear walls 1, side walls 2, and end walls 3. It will be noted that the end walls are provided with comparatively small apertures 4, the cross-section of each of which is less than the cross-section of the hollow space 90 5 within the block. It will also be noted that the end walls 3 are of greater thickness than the face walls 1 and side walls 2, so that a wall constructed of these blocks will have great strength at its bottom 95 joints. The side walls are provided with semi-oval shaped recesses A in order to receive vertical reinforcing bars B and the mortar which secures said bars in position. The end walls 3 of the block are provided 100 with grooves 6 which are arranged on opposite sides of the apertures 4 and are adapted to receive horizontally disposed reinforcing bars C and the mortar which secures said bars in position.

105

When the blocks are placed in a wall the hollow space 5 of each block communicates with the hollow spaces of the blocks above and below through the apertures 4 and owing to the present construction the apertures 4 will always be unobstructed as the grooves in the end walls 3 are spaced from

110

the apertures 4. Therefore the vertical passageways formed by the hollow spaces 5 and the apertures 4 permit the passage of electric conduits, sound tubes, plumbing pipes and the like. Further than this air may circulate within the hollow spaces and maintain the blocks in dry condition.

In Figures 8, 9 and 10 I have illustrated portions of walls constructed from the improved blocks, and in Figure 11 I have shown in detail the manner of connecting the blocks with the reinforcing metal bars B and C.

From the foregoing, I believe that the construction, advantages and operation of my improved blocks may be readily understood by those skilled in the art, and I am aware that various changes may be made in the construction illustrated, without departing from the spirit of the invention as expressed in the following claim:

What I claim and desire to secure by Letters Patent is:

A fire-proof artificial stone block having

oppositely disposed front and rear walls, 25 side walls connecting said front and rear walls together and provided with recesses designed to receive reinforcing metal bars and mortar for securing the side walls to adjacent blocks, thickened end walls connected to the front and rear and side walls, all of said walls enclosing a comparatively large interior chamber, each end wall being provided with a comparatively small aperture, the cross section of which is much 35 smaller than the front section of said chamber, and the end walls being provided with grooves arranged on opposite side of the end apertures and designed to receive reinforcing bars and mortar for securing the 40 block to blocks arranged above and below said block.

In testimony whereof he affixes his signature in the presence of two witnesses.

GENKICHI YAMANOUCHI.

Witnesses:

GENJI KUSIBARA,

P. KANENCH.
